UNITED STATES PATENT OFFICE.

MARCELAN N. CLAY, OF MORGAN CITY, LOUISIANA.

SPRING-WHEEL.

1,372,641.

Specification of Letters Patent. Patented Mar. 22, 1921.

Application filed May 8, 1918. Serial No. 233,327.

To all whom it may concern:

Be it known that I, MARCELAN N. CLAY, a citizen of the United States, residing at Morgan City, in the parish of St. Mary and 5 State of Louisiana, have invented new and useful Improvements in Spring-Wheels, of which the following is a specification.

This invention relates to a spring wheel and the object is to provide means for 10 resiliently mounting certain of the elements with reference to the axle in order to take up unusual vibration or shock due to obstacles encountered in the road way, or the uneven surface of the road way.

15 A further object is to provide means for resiliently mounting the axle with reference to the wheel proper, said means including a disk member carrying a plurality of laterally extending devices mounted thereon, the 20 wheel proper carrying inwardly and radially extending members located between the devices carried by the disk, and resilient members mounted between the several projecting devices, certain of the resilient members being 25 adjustable.

Figure 1 is a view of the wheel in elevation, the cover of the casing surrounding the hub being removed and portions of the casing and the mounting elements for the 30 springs being in section,

Fig. 2 is a vertical transverse section,

Fig. 3 is a fragmentary view, in section and elevation, showing a modified form,

Fig. 4 is a detail in section, showing the 35 springs mounted as in Fig. 3.

The rim of the wheel is designated 10, the spokes 11, and a casing or annular element having connection with the spokes and constituting a hub inclosing member is 40 shown at 12, this casing being provided with inwardly extending flanges 13 and 14.

Flange 14 and disk 15 are in approximate contact and are relatively movable, the latter carrying centrally a sleeve or hub 16 45 rigidly mounted and accommodating the axle 17. Extending inwardly from annular member 12 toward the axle is a series of stationary members 18 provided with ears 19 and apertures to permit of the pivotal 50 mounting of brackets 20 accommodating certain of the ends of the springs mentioned below. Between each pair of stationary members 18 is a resiliently mounted device 40, said device being pivoted at 23 to a 55 spring holding device or bracket 24. A spring 25 connects bracket 24 with a similar

bracket 26 pivotally mounted at 27 on an ear 28 carried by the annular casing member 12.

The springs 30 are located between pivotally mounted brackets or spring held devices 31, one of which is pivoted at 32 to ear 19 on stationary member 18 and the other of which is pivoted at 33 to member 35 constituting a fixedly mounted abutment. This member 35 is provided with a tubular 65 portion as shown and with laterally extending ears for pivotally mounting the holders or brackets 31 above referred to. Member 35 is rigid with reference to plate 15, as illustrated in Fig. 2. An adjustably mounted member which may be controlled by a key or the like extends into one end of the bore and is designated 38; being retained in position by a lock nut 39. The position of this member 38 determines the degree of 70 movement of a pin 40 pivotally connected at 41 with the bracket or spring holding device 24 retaining one end of spring 25 in position. Element 38 is threaded into the bore of member 35 and pin 40 is slidable 75 and abuts the end of member 38.

It is obvious that the several springs mounted as shown provide for taking up strains exerted in a direction or directions at substantially right angles with each other. 85

A second disk 5 opposite disk 15 is retained by suitable securing devices designated 6 passing through the disk 5 and flange 13.

In the modified form shown in Figs. 3 and 90 4 I have provided for adjusting a plurality of springs from one point. In this form the spokes of the wheel are designated 50, the annular member surrounding the hub is designated 51 and connected therewith are ears 95 52 to which spring securing devices 53 are pivoted. These devices may comprise bracket members portions of which may be of cup formation as shown in cross section in Fig. 4, although the section last indicated 100 illustrates more particularly the securing device for the other springs mentioned below. Connected with bracket 52 is a spring 54 having connection with a bracket 55 into which passes the threaded shank 56 of a 105 yoke member 57. An adjusting nut is shown at 58.

This yoke 57 is pivotally connected in the manner shown in Fig. 4, with a plurality of yokes 60 and 61 each having a threaded 110 shank 62 and 63 co-operating with a threaded aperture in one of the brackets or cup shaped

securing devices 64. A pin 59 mounted on disk 15 effects the pivotal connection for the yokes. Between these devices 64 and similar devices 65 are coil springs 66. Each securing device 65 is pivotally connected at 67 with a radial member 68 carried by the annular member 51 and extending inwardly therefrom. These members 68 are in line with the axis of the spokes. It will be observed therefore that the tension on either one of the springs above mentioned may be varied by making the required adjustment of the threaded shank 56, 62, or 63, as the case may be.

15 What is claimed is:

1. In a device of the class described, a rim, a plurality of spokes connected therewith, a casing mounted concentrically with reference to the rim and connected with the spokes, a disk member, a sleeve connected therewith and providing a bearing for an axle, said disk member closing one side of the casing, a second disk member closing the opposite side of the casing, a plurality of 20 stationary members projecting inwardly from the casing toward the axle and spaced

30 apart, means carried by the disk first named at spaced intervals and rigidly mounted thereon, said means projecting, respectively, between the stationary members on the casing, springs mounted between the stationary members and said means carried by the disk, an adjustable member retained in position by a pair of adjacent springs, and means 35 for connecting the adjustable member directly with the casing and including a resilient element.

2. In a device of the class described, a wheel comprising a hub, an annular casing surrounding the hub and connected therewith, a rim, spokes extending between the casing and rim, radially extending devices 40 projecting inwardly from the casing toward the hub, a resilient device connected with each of the radial devices, a spring and securing means connected with the casing at a point intermediate of the radial devices, and adjusting means centering at a common 45 point for adjusting the tension on the springs.

50 In testimony whereof I affix my signature.
MARCELAN N. CLAY.
